RESISTOR

Alfred E. Cobb, Lexington Park, Md.

Original application January 18, 1955, Serial No. 482,688, now Patent No. 2,847,543, dated August 12, 1958. Divided and this application June 26, 1957, Serial No. 668,265

3 Claims. (Cl. 338—76)

(Granted under Title 35, U.S. Code (1952), sec. 266)

The invention described herein may be manufactured and used by or for the Government of the United States of America for governmental purposes without the payment of any royalties thereon or therefor.

The present invention relates to a resistor and more particularly to a resistor which is variable.

A novel resistor is provided which is an integral part of an electrical apparatus, e.g. a card switch and thus the requirement for external resistors is obviated in some circuits and lessened in number in all circuits. Resistance material is painted on a piece of spring plastic material and is inserted on the underside of the spring contact bed and by construction and position is made to touch a whole row of spring loaded contacts in a circuit. Thus, a variable resistor is formed since a varying amount of resistance can be tapped off by a varying selection of spring loaded contacts.

This application is a division of application Serial No. 482,688, now Patent No. 2,847,543, issued August 12, 1958, filed January 28, 1955, for Card Switch System.

An object of the present invention is the provision of a resistor element for an electrical apparatus for producing a variable resistor.

Other objects and many of the attendant advantages of this invention will be readily appreciated as the same becomes better understood by reference to the following detailed description when considered in connection with the accompanying drawings wherein:

Fig. 1 illustrates an isometric view of a resistor which is adapted to be used in an apparatus.

Fig. 2 is an isometric rear and side view of an apparatus including the resistor shown in Fig. 1.

Fig. 3 shows a vertical section of the apparatus of Fig. 2.

Referring now to the drawing, wherein like reference characters designate like or corresponding parts throughout the several views there is shown in Fig. 1 a resistor 51 having a main body portion 52 and teeth 53 which are formed from one sheet of springy insulating material, such as a non-conducting plastic. Two insulated strips of resistance material 54 are painted on main body portion 52 and a conducting paint coating 55 is provided for teeth 53.

In Fig. 2 resistor 51 is shown situated among the undersides of spring loaded contacts 15 which extend through a support 14 comprising sheet 38, opening 41, and sheet 37. It may be desired to employ the resistor as a potentiometer in which case the end contact would

2

probably require grounding by a connection to clip 44. Only the pressure obtained by the spring action of the resistor 51 provides contact between rods 42 and teeth 53.

5 In Fig. 3, wires 61, 62 and 63 are shown connected to clips 44 on the contact rods numbered 64, 65, and 66. Rods 64 and 65 are shown extended through holes 18 in an insulating sheet 17 to join conducting bar 13. Resistors 51 connect the various rods 15. To obtain a 10 variable resistance, connections are required to the pins 36 which are connected to wires 61 and 62. The resistance path extends from wires 61 through rod 65 to bar 13, along bar 13 to contact 64, from contact 64 through resistors 51 to wire 62. It is obvious that the resistance 15 can be varied by merely changing the contact 64 that joins bar 13. If it is desired to have a potentiometer, the voltage supply is placed between wires 62 and 63 through suitable pins 36 mounted on a support 35 and wire 61 then has the variable voltage output. It is thus 20 seen that an unskilled operator can obtain a variable resistance or potentiometer by the insertion of the disclosed novel resistor in an electrical apparatus.

Obviously many modifications and variations of the present invention are possible in the light of the above teachings. It is therefore to be understood that within the scope of the appended claims the invention may be practiced otherwise than as specifically described.

What is claimed is:

1. In a bed containing a plurality of parallel rows of spring-loaded insulated single contacts; a resistor comprising a flexible insulated, springy material insert having a rectangular-shaped main body with appendages extending from the long sides of said main body, said resistor adapted by its springiness to be in pressure contact relationship with said spring loaded contacts, resistance material painted on the appendages and in two insulated strips adjacent to the appendages, and conducting paint superimposed on the resistance material on the appendages.

2. In a bed containing a plurality of parallel rows of spring-loaded insulated single contacts; a resistor comprising a flexible insulated, springy material insert having a body portion and side portions, said resistor adapted by its springiness to be in pressure contact relationship with said spring loaded contacts, resistance material on said side portions and in two insulated strips on said body portion, and conducting material on said side portions and in contact with said resistance material.

3. In a bed containing a plurality of parallel rows of spring-loaded insulated single contacts; a resistor comprising a flexible insulated, springy material insert having a body portion and fingers extending therefrom, said resistor adapted by its springiness to be in pressure contact relationship with said spring loaded contacts, resistance material on said fingers and in two insulated strips on said body portion, and conducting material on said side fingers and in contact with said resistance material.
